ELECTRIC OVERLOAD PROTECTIVE DEVICE

John B. Cataldo, Summit, N. J., and William E. Stilwell, Jr., Cincinnati, Ohio, assignors to John B. Pierce Foundation, New York, N. Y., a corporation of New York

Application December 5, 1942, Serial No. 467,956

6 Claims. (Cl. 200—113)

1

This invention relates to improvements in electric overload protective devices, otherwise known as circuit breakers.

It is an object of the invention to provide an improved circuit breaker of low cost and simple construction, especially for protecting an electric circuit against the effects of overloads or short circuits.

It is also an object of the invention to provide electric protective apparatus of the character described which may be employed in place of conventional plug fuses and the like.

It is an object of the invention to provide apparatus of the class described which will be "trip free," that is, which cannot be held in closed circuit position during the pendency of the overload or other abnormal condition in the electric circuit.

It is an object of the invention to provide overload protective apparatus which embodies a simple, conveniently arranged manual re-set to return the apparatus to operative position.

In a preferred form of the invention, we employ a snap-acting spring member, desirably in the form of a snap spring or disk, capable of assuming two positions of stable equilibrium, that is, capable of being snapped or upset from a concave form to a convex form, and vice versa, and maintaining such position. The snap spring is preferably mounted on an axially movable shaft, in connection with which elements there is a coil spring which urges the snap spring or disk in the direction of an organization of load-line contacts disposed at the ends of a preferably tri-legged bimetallic structure adapted for connection into an electric circuit. Most preferably, the snap spring is provided with silver button contacts for engagement with the contacts on the bimetallic element, although said snap spring contacts may, if desirable, be supplanted by an electro-plating or other coating of silver on one surface of the rim of the snap spring.

The snap spring assembly is desirably contained within a housing configurated internally to provide a shoulder immediately above the rim of the snap spring.

A manually operable push-pull button, or a bell crank pivoted within the housing is operatively associated with the aforesaid shaft to draw the latter and the snap spring respectively upwardly in the direction of and into engagement with the shoulder. Manual release of the button or bell crank, as the case may be, permits the coil spring to move the assembly, including the shaft and snap spring, back to its original posi-

2

tion, namely, such that the snap acting member contacts the aforesaid bimetal element.

Preferably one of the load-line terminals is connected to the snap spring. When the apparatus is in normal operating status, the snap spring, or the contacts thereof, are in electrical engagement with the contacts of the bimetallic element, which latter, in turn, are connected to the other load-line terminal. By suitable design or calibration of the bimetallic member, the legs thereof will start to warp upwardly, under the heating effect of overload electric current passing therethrough or short circuit. The upward movement or continued warping of the bimetal element exerts a continually increasing pressure against the rim of the snap spring until its overthrow or upset point is reached, whereupon the spring will reverse its position of equilibrium, and the contacts thereof will be drawn away from engagement with the contacts of the bimetallic member, with great rapidity. The circuit will then be broken and the legs of the bimetallic member, upon cooling, will return to their initial position.

Because of the two equilibrium point characteristic of the snap spring, it will remain in inverted position, in which position the rim will engage, or be closely proximate, the aforesaid shoulder of the aforesaid housing. To return the snap spring to initial or closed circuit position, it is only necessary that the shaft upon which the spring is mounted be moved upwardly, whereupon the edges of the snap spring will be brought forcibly against the shoulder and the snap spring will, by the reaction pressure, be inverted to its initial shape. This is accomplished by manual displacement of the push-pull button or bell crank lever from its normal position. However, the snap spring will still be elevated or out of contact with respect to the contacts of the bimetallic element so long as said manual displacement is imposed; and so long as the snap spring is thereby held in its retracted position, it will be impossible to re-close the electric circuit. In other words, it is impossible to hold the circuit breaker in closed circuit position.

However, immediately upon release of the manual element, the coil spring will drive the snap spring assembly downwardly as a unit and the snap spring into contact with the bimetal member, whereupon the circuit will be closed. If the abnormal condition causing the overload or short circuit has not been remedied, the cycle of operation will be repeated, namely, the bimetal ele-

ment will automatically upset the disk again to break contact therebetween.

The relative movement of the rim of the snap spring is availed of to actuate indicator means to show whether or not the snap spring is in open or closed circuit position. Such indicator, in a preferred form, may comprise a rod or pin passing through an aperture in the housing of the unit and bearing lightly against the rim of the snap spring. With the snap spring in normal operating position, the upper end of the pin is concealed wholly within the housing; when the snap spring snaps or upsets to open circuit position, the displacement of the rim lifts the indicating rod to a position where its upper end projects above the surface of the device, thereby affording a visual indicator of the operative status of the apparatus.

Our improved apparatus lends itself conveniently to application in plug connectors, such as the removable cord connector of an electric iron or the like, or plug connectors to afford individual protection for apparatus equipped with conventional, non-fused, attachment plugs.

Further features and advantages will herein-after appear.

In the drawings:

Fig. 1 is a vertical sectional view of a circuit breaker embodying the present invention;

Fig. 2 is a section similar to Fig. 1, but taken at right angles thereto;

Fig. 3 is a sectional view taken on lines 3—3 of Fig. 1, showing the disposition of the bimetallic member;

Fig. 4 is a sectional view taken on lines 4—4 of Fig. 1, illustrating a preferred form of snap spring;

Fig. 5 is a top view of the device of Fig. 1;

Fig. 6 is an enlarged detail showing, fragmentarily, the connection of the operating shaft and coil spring with the snap spring;

Figs. 7 and 8 are sectional views illustrating incidents in the operation and re-setting of the device of Fig. 1;

Fig. 9 is a vertical section showing another embodiment of the invention in the form of an attachment plug;

Fig. 10 is a view similar to Fig. 9, but showing another embodiment of the invention in the form of an outlet plug tap; and

Fig. 11 is a plan section taken through 11—11 of Fig. 9.

In the embodiment illustrated in Figs. 1 through 8, the invention is illustrated as applied to a screw type plug comprising a housing consisting of a base 20, an intermediate cylindrical member 21 and a cap 22, all of which may be formed from glass and assembled after the respective internal operating parts are positioned, and made inseparable, if desired, by welding the glass elements together pursuant to known manufacturing processes.

The base 20 is molded and provided with three radially arranged slots or recesses, see Fig. 3, each of which successively increases in depth to a maximum depth at the center of the base. Within these slots is disposed a tri-legged bimetallic element 23, the hub of which is secured to the base by the illustrated rivet 24. The external end of the rivet forms a load line contact 25, see also Fig. 1. The legs of the bimetallic structure are unsecured, and at the end of each of said arms there is provided a suitable contact 26, preferably a silver bead or the like.

Within the intermediate body member 21, 75 we provide in the instant embodiment a bell

there is positioned a circuit breaker organization, an essential element thereof being a snap spring 27, preferably in the form of a three-spoked annular disc, said snap spring being so dished that it assumes either a convex form as shown in section in Fig. 1, or a concave form, as shown in Fig. 7, each of said forms being a position of stable equilibrium of the spring.

For engaging the respective contacts 26 of the bimetallic structure, the snap spring 27 may have similar silver button contacts 28, see Fig. 1, or if preferred, the entire face of the rim of the snap spring may be silver plated or otherwise provided to function as a contacting surface of suitable conductive material. Fixed to the center of the snap spring, see Fig. 6, is a shaft 30, a reduced diameter end of which passes through the snap spring. The tip of said shaft is flared and engaged by a collar 31, which bears against the central portion of the disk and between which and a washer 32 the disk is secured to the shaft 30. Surrounding said shaft 30 and preferably bearing against washer 32, is a coil spring 33, the other end of which bears against the shoulder 34 of the intermediate body portion 21. Suitably electrically connected to the structure of the snap spring 27 is a conductor 35 which is of relatively flexible material and connected by means of a solder joint or equivalent to the outer shell conductor member 36 of the device, as illustrated in Fig. 1.

It will be seen that when employed in lieu of a conventional plug fuse, the contact 25 is arranged to make electrical connection with one of the lines of an electrical circuit, and the shell 36 provides the connection with the other or return line of the circuit. It will be seen also that with the elements in their Fig. 1 position, the path of electric current is through the respective legs of the bimetallic structure, thence to the snap spring 27, and, through the conductor 35, to the shell contact 36.

The bimetallic structure 23 is formed of materials of suitable character and current carrying capacity, to warp under the heating influence of electric currents of predetermined values. Since the bimetallic structure is secured only at its center point, and with the materials of the bimetal structure suitably arranged with respect to their coefficients of expansion, the increase in temperature in such a bimetallic structure is utilized to warp the legs thereof upwardly, in which circumstance they will press against the snap spring 27. After the exertion of a suitable pressure, which may be determined in advance from the warping response of the bimetal element and the throw characteristic of the snap spring, said snap spring 27 will invert or upset, and in so doing, will lift its contacts 28 out of engagement with the contacts 26 of the bimetallic structure, thereupon breaking the circuit.

As previously stated, the snap spring 27 is so formed that it has two positions of stable equilibrium, and therefore, it will remain in its inverted position indefinitely. The body portion 21 has a shoulder 37, see Fig. 2, adjacent which the rim of the snap spring 27 rests, see Fig. 7, when the snap spring is in inverted position. It will be obvious, therefore, that by moving the snap spring bodily upward, as by lifting the shaft 30, the reaction pressure of the rim of the snap spring against shoulder 37 will cause it to snap back into its original position. To manually accomplish such a reverse movement of the spring, we provide in the instant embodiment a bell

crank lever 38, the free end of which passes through a suitable aperture in the cap 22 and the opposite end of which is pivotally connected to the shaft 30 as shown in Figs. 1 and 2. The bell crank lever is fulcrumed on the upper surface of the shoulder 34 by the illustrated lug 38a. Lateral displacement of the free end of said lever causes said bell crank to raise the shaft 30 to effect the snapping of the spring 27 to its initial convex position.

The displacement of the snap spring 27 and the contacts thereof relative to the bimetal structure 23 is such, under the stated condition, that when the snap spring is returned to its original convex position under the action of the bell crank 38, the respective contacts of the snap spring and the bimetallic structure do not meet and the circuit is not closed. Therefore, it is not possible to hold the circuit breaker closed by continued manual displacement of the bell crank lever 38. It is only when the lever is released that the snap acting disk is enabled to make contact with the bimetal element.

As illustrated in Fig. 2, an indicator to reveal the relative position of the snap spring 27 may comprise a light, flexible rod 39 resting, under the influence of a light coil spring 39a, upon the rim of the snap spring 27. With the apparatus in normal closed circuit position, the upper end of the rod 39 is flush with, or beneath, the surface of the cap 22, thus being unnoticeable. When the snap spring throws to open circuit position, however, the rising of the rim of said snap spring causes the rod 39 to be driven upwardly, in which circumstance its upper end appears above the surface of the cap 22, thereby indicating that the circuit breaker has been thrown to open circuit position.

Fig. 7 is representative of the various embodiments of our invention described herein, in depicting the action of the overload protection afforded by our invention immediately after the legs of the bimetallic structure 23 have risen under the influence of temperature generated by the passage of excess electric current therethrough, and have exerted such pressure upon the snap spring 27 that the snap spring is displaced to its inverted, i. e., concave position of stable equilibrium. It will be noted that in such position, the contacts 28 of the snap spring are displaced from the contacts 26 of the bimetallic member, and that the rim of the snap spring is raised against or closely adjacent to the shoulder 37 of the body member 24. In such position, the circuit has been broken.

In Fig. 8, it is shown how the action of the bell crank 38, is effective to draw the shaft 30 upwardly against the tension of the coil spring 33, and has caused the snap spring 27 to invert itself to its original convex position. Fig. 8 also shows that such inversion of the snap spring is not of itself sufficient to restore electric contact between the contacts 28 and 26 respectively of the snap spring and bimetallic member. Therefore, even if the bell crank 38 were actuated before the bimetallic structure had cooled sufficiently to bring its legs back into normal position against the base 20, the electric circuit could not be closed, because the raised position of the snap spring 27 resulting from manual displacement on the bell crank lever 38 and consequent upward movement of the shaft 30 prevents the snap spring from moving into engagement with the bimetallic element 23. The circuit breaker may not, therefore, be held in closed circuit posi-

tion. However, upon releasing the lever 38, the shaft 30 and the snap disc spring 27 are automatically projected by the coil spring 33 to effect electrical connection of the snap disc spring with the contacts of the bimetallic element 23.

Referring to Figs. 9 and 10, our invention is illustrated respectively as applied to an attachment plug and an outlet plug tap.

In the embodiment of Figs. 9 and 11, an outer shell 40 contains an assembly housing the snap spring and bimetallic members; the lower portion of the housing provides a chamber for connection of the cord C. Said housing includes a cup 41, the base of which is channelled as previously described with respect to the base 20 of the Fig. 1 embodiment, to receive the tri-legged bimetallic member 23, secured at its central point to the cup 41 by a rivet 42 serving also to connect the bimetallic element with a terminal 43, for connection with a conductor of the electrical cord C.

The snap spring 44, in this embodiment shown with an overlaid continuous contacting surface 45, is carried by a spring biased shaft 30, the coil spring 33 thereof and elements supporting the shaft 30 on the snap spring 44 being arranged as shown in Fig. 6. Instead of the bell crank 38, however, the shaft 30 is provided with a button-head 46 which may be manually grasped to raise the shaft 30 against the tension of coil spring 33.

Snap spring 44 is electrically connected to a plug blade 47 by means of a flexible connection 48.

The snap spring assembly is carried by a plug portion 50 molded with a coarse male thread to permit its easy and permanent securement to and within the cup 41. If desired, suitable adhesive may be applied to rigidify the connection between the plug 50 and the cup 41.

The second plug blade, 51, is the termination of a bus-bar having a terminal 52 serving as a connector for the other conductor of the electric cord C; a central portion 53 of said bus-bar lies within a channel 54 of the cup member 41, see Fig. 11. The intermediate angularly offset elements, respectively overlie end surfaces of the plug 50 and the cup 41, in tight engagement therewith.

Fig. 9 illustrates the connectors of the electric cord C secured to the terminals 43, 52, as by conventional set-screws.

In assembling the Fig. 9 embodiment, the plug 50 and therewith associated snap spring organization is screwed into the cup 41, see Fig. 11, and the central portion 53 of the bus-bar is laid in the channel 54, being held in position by the tight engagement of the offset portions with the end surfaces of the plug 50 and cup 41.

In connecting the terminals of the cord C, the shell 40 is removed by merely unscrewing it from the inner assembly. The end of the cord C is passed through the illustrated aperture in the shell and the wires of the cord C connected as shown, whereupon the shell may be re-screwed to the cup 41.

The device illustrated in Fig. 10 corresponds generally to that of Fig. 9, except with respect to the spring contacts 42a, 52a, and the provision of plug-blade slots 40b in shell 40a. The shell 40a, when initially secured to the cup 41 at the completion of manufacture, need not again be removed.

The operation of the Figs. 9 and 10 embodiments is similar to that previously described with

respect to the Fig. 1 embodiment. When the snap spring 44 has inverted under the action of the bimetal element 23, its rim is disposed beneath the edge of the plug 50, whereupon grasping the button 46 and drawing it outwardly is sufficient to restore the snap spring to its initial concave form. When the button 46 is released, the snap spring 44 is moved by the coil spring 33 in the direction of the bimetallic element to make contact therewith. It is obvious, however, that it is necessary to remove the device from the outlet into which it had been plugged, to manipulate the button 46. It is impossible, therefore, to hold the circuit breaker closed, and the necessary removal of the devices from association with the electric circuit precludes any possibility of shock to the operator in handling the button 46.

Whereas we have described our invention by reference to specific forms thereof, it will be understood that many changes and modifications may be made provided they do not depart from the scope of the claims.

We claim:

1. An electric circuit breaker comprising a housing, a thermostatic metal structure secured within said housing, snap disc spring means possessing two positions of stability movably positioned within said housing and disposed in operative relationship to said thermostatic metal structure, resilient means for urging said snap spring into electricity conductive contact with said thermostatic metal structure when said snap spring means is in one of its positions of stability, means for connecting said snap spring and said thermostatic metal structure in series in an electric circuit, said thermostatic structure having a portion displaceable under increase in temperature and arranged to exert pressure against said snap disc spring means, whereby under the heating effect of predetermined values of electric current said thermostatic structure causes said snap spring means to be thrown out of engagement with said structure to its second position of stability to break said series circuit, said housing being provided with inwardly extending abutment means positioned proximate the rim of said snap disc spring means when said snap disc spring means is in its said second position of stability, and means accessible externally of said housing for moving said snap disc spring means to abut said abutment means to thereby invert said snap disc spring means to its said initial position.

2. Apparatus as defined in claim 1, wherein the securing means for said snap disc spring means includes a shaft supporting said snap disc spring means and a coil spring effective to move said shaft and snap disc spring means in the direction of said thermostatic metal structure.

3. Apparatus as defined in claim 1, wherein said snap disc spring means comprises a circular dished spring member and said thermostatic metal structure has a plurality of freely movable legs adapted to bear against the rim of said snap spring.

4. An electrical circuit breaker comprising a housing, a thermostatic metal structure secured within said housing, a substantially circular spring member possessing two positions of stability movably mounted within said housing and disposed in operative relation with said thermostatic metal structure, resilient means for urging

said substantially circular spring member into electrical contact with said thermostatic metal structure when said substantially circular spring member is in one of its positions of stability, means for connecting said substantially circular spring member and said thermostatic metal structure in series in an electrical circuit, said thermostatic structure having a portion displaceable under increase in temperature and arranged to exert pressure against said substantially circular spring member whereby under the heating effect of predetermined values of the electrical current of such electrical circuit said thermostatic structure causes said substantially circular spring member to be thrown out of engagement with said thermostatic metal structure and to its second position of stability to thereby interrupt such electrical circuit, abutment means disposed within said housing arranged to engage the rim of said substantially circular spring member when the latter is in its position of interrupting such electrical circuit, and means for displacing said substantially circular spring member when in its said circuit interrupting position to engage said abutment means to thereby cause said substantially circular spring member to invert to its opposite position of stability.

5. Apparatus as defined in claim 4 wherein said resilient means is a coil spring for urging said substantially circular spring member into electrical contact with said thermostatic metal structure.

6. An overload protected attachment plug, comprising a cup member having a thermostatic member secured at the base thereof, a hollow plug member insertable with said cup member, said plug member having a snap disc spring disposed therein, said snap disc spring having two positions of stability, in one of which positions said snap disc spring is in contact with said thermostatic member, means for connecting said snap disc spring and said thermostatic member into an electric circuit, a housing for said assembly cup and hollow plug member, said housing being provided with inwardly extending abutment means positioned proximate the position of the rim of said snap disc spring when said snap disc spring is in its position out of contact with said thermostatic member; shaft means extending into said hollow plug member; a coil spring engaging said shaft means and abutting at its one end with said snap disc spring and at its opposite end against a fixed support; and means extending exteriorly of said housing for operating said shaft means to thereby move said snap disc spring to engage at its rim with said abutment means whereby such engagement with said coil spring causes said snap spring to invert to its opposite position of stability.
